Primary Examiner — Eric L Goodman*Assistant Examiner* — Amy C Wierenga(74) *Attorney, Agent, or Firm* — Kilpatrick Townsend & Stockton LLP(57) **CLAIM**

The ornamental design for a garment, as shown and described.

DESCRIPTION

FIG. 1 is a front view of an embodiment of a garment.

FIG. 2 is a rear view of the garment of FIG. 1.

FIG. 3 is a right side view of the garment of FIG. 1, it being understood that the left side is a mirror image of the right side view.

FIG. 4 is a top view of the garment of FIG. 1; and,

FIG. 5 is a bottom view of the garment of FIG. 1.

The dash dot broken lines immediately adjacent to shaded areas represent unclaimed boundaries of the claimed design. The remainder of the garment shown in broken lines depicts environmental subject matter only and forms no part of the claimed design.

1 Claim, 5 Drawing Sheets# US D809,245 S
